Des. 241,460
Patented Sept. 14, 1976

241,460

NOVELTY TOY RAZOR

John S. Holzli, Newton, N.J., assignor to
J. J. Jesk Company, Newton, N.J.

Filed Mar. 28, 1974, Ser. No. 455,886

Term of patent 7 years

Int. Cl. D21—01

U.S. Cl. D34—15 R

FIG.1

FIG. 2

FIG. 3

FIG. 4

FIG. 1 is a front elevational view of a novelty toy razor showing my new design;

FIG. 2 is a right side elevational view thereof, the side opposite being substantially a mirror image;

FIG. 3 is a top plan view thereof; and

FIG. 4 is a bottom plan view of the novelty toy razor of FIG. 1.

I claim:

The ornamental design for a novelty toy razor, as shown and described.
